UNITED STATES PATENT OFFICE

ANDREW HOFFMAN, OF CHICAGO, ILLINOIS, ASSIGNOR TO ANDREW HOFFMAN MANUFACTURING COMPANY, OF CHICAGO, ILLINOIS, A CORPORATION OF ILLINOIS

DISPLAY RAIL

Application filed August 28, 1926. Serial No. 132,138.

The object of this invention is to provide of generally U-shaped cross section, and is an improved device which may be used to support maps, charts, pictures and like display matter from a wall in a school room, 5 picture gallery or similar place. The device may also be used in a great many other different ways.

The device is not only susceptible of being shifted from one location to another or 10 moved entirely from the wall, but is exceedingly simple and inexpensive to manufacture, is equally strong at all points throughout its length, and may be applied as an inconspicuous inlay in trim, or in any other 15 desired manner.

While the foregoing statements are indicative in a general way of the nature of the invention, other objects and advantages will 20 be apparent to those skilled in the art upon a full understanding of the construction, arrangement and operation of the improved device.

A preferred form of the invention is presented herein for the purpose of exemplification, but it will of course be understood that the invention is also susceptible of embodiment in other slightly modified forms coming equally within the comprehensive scope 25 of the appended claims.

30 In the accompanying drawing:

Fig. 1 is a fragmentary perspective view showing the device applied to the trim on a wall;

Fig. 2 is an enlarged section through the 35 device, showing the article-supporting member of the device in operative position in the rail;

Fig. 3 is a similar view, showing the article-supporting member while being removed from the rail; and

Fig. 4 is a perspective view of the article-supporting member.

It will be observed in the drawing that the device of the invention includes a channel rail 10 and an article-supporting member 11 in association therewith. Only one article-supporting member is illustrated, but the use of a number of such members is contemplated.

50 The channel rail 10 is a sheet metal strip

provided with upper and lower flanges 12 and 13 which extend toward each other. The article-supporting member 11 includes a block 14 of generally rectangular form 55 which fits within the channel in the rail. The block is of slightly less height than the channel, as shown in Fig. 2, and is beveled at 15 in order to permit the lower end 16 of the block to be swung outwardly when the 60 block is being removed from the rail in the manner hereinafter described. The block may also be grooved at 17 in order to clear the countersunk heads of the screws 18 used to attach the rail to the trim 19. A hook 65 20 projects outwardly from the block through the slot formed between the upper and lower flanges of the rail, and constitutes a convenient and adjustably positioned projection from which various articles may be 70 suspended.

The lower flange 13 of the rail is provided in its upper edge with a shallow notch 21 of slightly greater length than the block 14. The notch 21 serves to permit the block to be 75 inserted in or removed from the channel in the rail, when it is desired, for instance, to remove the block from the rail, it is first shifted into a position opposite the notch 21. It is then raised slightly to permit the lower 80 end 16 thereof to clear the bottom of the notch 21, whereupon it may be swung out of the channel, as shown in Fig. 3.

When the device is in use, the weight of the article suspended from the hook 20 is 85 transmitted by the block 14 to the upper flange 12 of the rail, and, inasmuch as such flange and the adjoining portions of the rail are not weakened by the provision of any interruptions therein, but are continuous, the 90 device is able to support equally heavy loads at all points throughout the length of the rail, irrespective of whether or not the block 14 happens to be positioned opposite the notch 21 in the lower flange.

The channel rail 10 need not necessarily be in the form of a single strip, but may be made up from several strips arranged together in such a way as to provide a hollow structure having at the top a downwardly extending 100

wall portion which is free from notches and at the bottom an upwardly extending wall portion which is provided at intervals with notches.

5 I claim:

1. A device of the character described, comprising a hollow rail provided with a slot in the front face thereof and a notch in the lower edge of the slot spaced above the bottom of the rail, and an article-supporting member slidably positioned in the rail, said member being of slightly less height than the distance between the bottom of the notch and the inside top wall of the rail and being vertically shiftable in the rail and removable therefrom upon being raised and tilted while in a position opposite the notch.
2. A device of the character described, comprising a channel rail provided with upper and lower marginal flanges which extend toward each other and form a partially closed channel of generally rectangular form, and a block of generally similar form positioned in the channel, said block having a thickness substantially equal to the depth of the channel and having the upper rear corner thereof beveled; and said lower flange having an interruption therein of such size as to permit the lower edge of the block to be swung forwardly through the interruption by reason of the bevel when the block is in a position opposite the interruption.
3. A device of the character described, comprising a channel rail provided with upper and lower marginal flanges which extend toward each other, screws extending through apertures in the back of the rail for attaching the latter, and an article-supporting member having a base slidably positioned in the channel of the rail and provided with vertically spaced bearing projections on the rear face thereof above and below the level of the apertures in the rail for sliding engagement with the opposite portions of the rail, said base inclusive of the projections having a thickness substantially equal to the depth of the channel.

In testimony whereof I have hereunto subscribed my name,

50 ANDREW HOFFMAN.
